ELECTRICAL INSTRUMENT

Application filed May 24, 1928. Serial No. 280,145.

This invention relates to electrical measuring instruments and while not limited thereto aims particularly to provide means whereby a single instrument may be utilized to graphically indicate successive records of voltage for different circuits.

The invention will be apparent from the following specification when read in connection with the accompanying drawings and 10 will be defined with particularity in the appended claims. In the drawings—

Fig. 1 is a diagrammatic view showing the application of the invention to a recording voltmeter and connected to a polyphase power 15 distribution circuit;

Fig. 2 is an enlarged longitudinal section of a circuit controlling device shown in Fig. 1;

Fig. 3 is a transverse section on line 3—3 20 of Fig. 2;

Fig. 4 is a view of a portion of a graphic chart having a record thereon indicating the voltage of different circuits during successive time intervals.

25 In the distribution of electrical energy one of the systems in general use is known as the three-phase, four wire secondary system. Such a system is diagrammatically indicated in Fig. 1 wherein feeders are usually placed 30 in the street from which most light and power consumers are supplied, are indicated at A, B and C. These feeders are connected through suitable intermediate distribution equipment at the power house, not shown, 35 with the secondary windings *a*, *b* and *c* of a three-phase alternating current transformer. This connection is the well known, so-called "Star" or Y arrangement in which there is a phase difference between conductors A, B 40 and C of 120 degrees. The neutral point 0 of the circuit is connected to ground as indicated at *g* and a ground conductor G also parallels the conductors A, B and C through the secondary street mains. It is customary to 45 supply different customers by at some points tapping the wires A and B and at other points by tapping the wires B and C and at still others, by tapping the wires C and A. In each case the consumer's service is also connected with the ground conductor G. Such

service connections are indicated diagrammatically at 1, 2 and 3. One of the necessary and essential requirements of a power distribution system of this kind is to maintain a substantially constant voltage between the 55 phases A, B and C regardless of the load variations occasioned by varying power demands of the different customers and other disturbing conditions. It is, therefore, very desirable that a permanent record be made at 60 the different points on the feeders A, B and C so that the power companies can detect the time and extent of any abnormal variations in voltage so as to aid in identifying 65 their cause.

To secure these records it is the present practice to insert a recording voltmeter between the neutral line G and one of the conductors A, B or C. This is not wholly satisfactory because it is a record of but one of the 70 three phases. The other two phases being in a measure independent of each other and the phase being recorded, may each have variations of their own which will not show up to the corresponding extent on the record of 75 the phase in which the instrument is connected.

Of course, two additional recording instruments could be installed for the other two phases. However, this would require three 80 instruments for each recording station. This would necessitate a costly installation of recording instruments. But even with three instruments exact comparison cannot readily be made because of the difficulty in exactly 85 calibrating three instruments.

To meet this problem, I provide means whereby a single instrument may be utilized to measure the voltage between each of the wires A, B and C and the neutral wire G. 90 The record for the three phases being made by the same instrument is exactly comparable because any error in calibration is the same for each phase measured. The device is also designed to permit of ready identification of 95 the particular phase for which the record is made. I secure a distinctive identifying record for each phase or circuit by varying the time interval for which each circuit is operative so that a different length of graph 100

is given for each phase or I may make two graphs of equal length and a third of shorter length. Inasmuch as the graphs will always follow in the same sequence, the different 5 phase or circuit readings can be readily distinguished as will hereinafter more fully appear.

In an embodiment of the invention illustrated, I provide a circuit changing device 10 indicated as a whole by numeral 10. This includes a shaft 12, one end of which carries a gear 14 meshing with an idler 16 which meshes with a gear 18 secured on a shaft 20 carrying a roller 22. The roller 22 is part of 15 a standard recording voltmeter which is driven through a suitable gearing by a timing device diagrammatically indicated at 30 forming part of the recording voltmeter. This timing device may be either clock-driven 20 or electrically driven. The recording voltmeter as shown includes a supply roll 32 on which the record or chart sheet 34 is carried. This sheet passes over roll 36 and a fixed 25 platen 38 and is wound up on a take-up roll 40 which is driven in the usual manner by means not shown or described as they form no part of the present invention.

The recording voltmeter includes the usual stylus 42 carried on the end of a needle 44 30 which is pivoted at 46 and adapted to be deflected from one side to the other by variations in voltage by means of the usual voltmeter coil 48.

One end of this coil is connected through a 35 resistance R and wire 50 with the ground or neutral wire G. The other end of the coil 48 is connected by wire 52 with a brush 54 which rides on a contact ring 56 secured to and carried by an insulated bushing 58 which turns 40 with the shaft 12.

The insulator sleeve 58 is surrounded by a torsion spring 60, one end of which is electrically and mechanically connected to the ring 56 and the other end of which is similarly 45 connected to a conductor tooth 62 secured to a fibre insulating collar 64 which loosely engages the shaft 12.

Located at unequally spaced angular intervals around the axis of the shaft 12, I provide 50 contact members 66^a, 66^b and 66^c which are adapted to successively coat with the conductor tooth 62. The brushes 66^a, 66^b and 66^c are connected by wires 68^a, 68^b and 68^c, respectively, with the feed wires A, B 55 and C.

The contact members 66^a, 66^b and 66^c are each carried by a respective stud similar to that shown at 70, in Fig. 2, and each contact member is provided with a volute spring portion 72 secured to the stud, the extremity of each contact member being bent at right angles as indicated at 74 so as to provide a 60 detent adapted to engage the tooth 62 and thus normally prevent counter-clockwise rotation of the collar 64.

Secured to the shaft 12 alongside the collar 64 I provide a cam 76 made of fibre or similar insulating material and having a projection 78 which is adapted to successively engage the detent portions 74 of the respective contact members 66^a, 66^b and 66^c so as to free them from the tooth 62. As thus arranged, it is clear that as the cam 76 rotates the collar 64 and tooth 62 carried thereby will successively snap to engagement with the 75 three contact members 66^a, 66^b and 66^c.

Thus, it is clear that when the tooth 62 is in engagement with the contact member 66^a a circuit will be established from feed wire A through wire 68^a, contact member 66^a, tooth 62, spring 60, ring 56, brush 54, wire 52, voltmeter coil 48, resistance R, conductor 50 and ground or neutral wire G. For the interval of time that this connection is made, the stylus B will make the graph indicated at A' 80 in Fig. 4. When the cam projection 78 trips contact 66^a, the torsion spring will snap the tooth 62 into engagement with the end of the contact member 66^b. Therefore, for the next time interval, the stylus 42 will make 85 the graph indicated at B' in Fig. 4. Similarly, when the cam projection 78 trips the contact 66^b, the tooth 62 will snap to engagement with the contact 66^c, whereupon, for the third interval, the stylus will make the 90 graph indicated at C' in Fig. 4. The peripheral spacing between the ends 74 of the contact members 66^a, 66^b and 66^c is preferably unequal so that the graphs A', B' and 95 C' will each be of a different length. The length as measured longitudinally of the chart sheet 34 serves to identify the circuit whose value is indicated by the graph. Thus, as graphically indicated in Fig. 4, the longest graphs A' will indicate the voltage between 100 feeder A and neutral G. The graphs B and C will similarly indicate the voltage across the feeders B and C, respectively and the neutral or ground wire G.

Because of the momentary breaking of the 110 circuit each time the cam projection 78 trips contact members 66^a, 66^b and 66^c, the stylus 42 will make a quick lateral deflection which will be effective to mark the lateral dividing lines d between the different graphs A', B' 115 and C'. Because of the rapidity with which the torsion spring 60 acts, the voltmeter needle 44 will not jump to zero upon breaking of the circuit, thus, the instrument will not be subjected to such an excessive wear or shock as would be occasioned if the circuit remained open for a longer period.

The angular spacing between the ends 74 of the respective contact members 66^a, 66^b and 66^c being unequal and the shaft 12 being driven at a constant rate by the timing device, it follows the separate circuits will be 120 sustained through the coil of the meter which actuates the stylus for separate predetermined time intervals. Thus, the longest 125

graph A' of Fig. 4 can be identified with the voltage characteristic of the circuit including wire B and ground conductor G. Similarly, the next shorter graph B' will indicate the voltage across wire B and conductor G.

5 And the shortest graph C' will indicate the voltage between the wire C and G. Thus, it is clear that by providing means for successively sustaining separate circuits through the different phases for different time intervals, I provide a novel means of identification.

In recording voltage on electric service distribution networks, it is of no importance that the graph for each phase be of exactly 15 the same length. It is only necessary that the frequency at which the graphs A', B' and C' are made is such as to give a substantially true record of voltage variations during a given day of twenty-four hours.

20 If the graphs for the circuits were all the same length, the record would be of little practical use because of lack of identification. But, by making them of varying lengths, one can tell at a glance to which 25 phase or circuit the graph refers.

The making of separate identifiable voltage graphs of the different phases or circuits on a single chart, instead of using a separate instrument for each phase, has the 30 added advantage that the record graphs obtained are exactly comparable, as any error in the instrument or in the calibration is the same for all three phases. On the other hand, in using three separate instruments, 35 the calibration is apt to vary and there are three chances for error due to faulty response of each instrument.

From the foregoing it is clear that I provide means whereby a single meter and single chart is operative to produce a distinctive and readily identifiable record graph for each phase of a polyphase circuit or of 40 a plurality of separate circuits.

While I have described with great particularity certain specific details of the construction and arrangement of parts, it is not to be construed that I am limited thereto since various modifications and substitution of equivalents may be made by those skilled 50 in the art without departing from the invention as defined in the appended claims.

What I claim is:

1. In combination with a recording voltmeter having a timing device and a chart 55 moved at a constant rate thereby, a circuit changing mechanism driven at a rate commensurate with that of the chart, said circuit changing mechanism comprising a plurality of unequally spaced yielding contact members, a rotary circuit closing member mounted for coaction with said contact members, said contact members being arranged to normally oppose the movement of said 60 rotary circuit closing member, spring means 65 tending to turn said circuit closing member

and means for periodically tripping said yielding contact members so as to successively release the rotary circuit closing member after a lapse of a predetermined time interval.

2. In combination with a recording voltmeter having an actuating core, a chart moved at a substantially constant rate, a circuit changing device including a shaft driven at a rate commensurate with that of the chart, a plurality of contacts electrically connected with separate conductors, a member loosely carried on said shaft for coaction with said contacts, means tending to turn said member relatively to said shaft, said contacts being arranged to prevent said turning movement, means for successively tripping said contact members, a contact ring on said shaft electrically connected with said member and a brush engaging said ring which is connected through the voltmeter coil with a conductor.

In witness whereof, I have hereunto signed my name.

ALBERT J. ALLEN.
